(57) **CLAIM**

The ornamental design for the blade case, as shown and described.

DESCRIPTION

FIG. 1 is a front elevational view of a blade case showing the new design, with the rear elevational view being a mirror image;

FIG. 2 is a top plan view thereof;

FIG. 3 is a bottom plan view thereof;

FIG. 4 is a right side elevation view thereof;

FIG. 5 is a left side elevation view thereof;

FIG. 6 is a cross section thereof taken along line A-A in FIG. 2;

FIG. 7 is a perspective view thereof showing the front, top, and right side;

FIG. 8 is a perspective view thereof showing the front, bottom, and right side;

FIG. 9 is a perspective view thereof showing the top in an open state;

FIG. 10 is a perspective view thereof showing the bottom in an open state;

FIG. 11 is a front elevational view of a case body portion thereof, with the rear elevational view being a mirror image;

FIG. 12 is a top plan view of the case body portion thereof;

FIG. 13 is a bottom plan view of the case body portion thereof;

FIG. 14 is a right side elevational view of the case body portion thereof;

FIG. 15 is a left side elevational view of the case body portion thereof;

FIG. 16 is a perspective view of the case body portion thereof showing the rear, top, and right side;

FIG. 17 is a perspective view of the case body portion thereof showing the rear, bottom, and right side;

FIG. 18 is a front elevational of a lid portion thereof, with the rear elevational view being a mirror image;

FIG. 19 is a top plan view of the lid portion thereof;

FIG. 20 is a bottom plan view of the lid portion thereof;

(Continued)

FIG. 21 is a right side elevational view of the lid portion thereof;
FIG. 22 is a left side elevational view of the lid portion thereof;
FIG. 23 is a perspective view of the lid portion thereof showing the front, top, and right side; and,
FIG. 24 is a perspective view of the lid portion thereof showing the front, bottom, and right side.
The blade case lid and body are shown separately in FIGS. 11-24 for convenience of illustration only.
